UNITED STATES PATENT OFFICE.

ROBERT S. COOPER, OF HUMPHREYS, MISSOURI.

VICE.

SPECIFICATION forming part of Letters Patent No. 440,543, dated November 11, 1890.

Application filed April 5, 1890. Serial No. 346,695. (No model.)

To all whom it may concern:

Be it known that I, ROBERT S. COOPER, a citizen of the United States, residing at Humphreys, in the county of Sullivan and State of Missouri, have invented certain new and useful Improvements in Vises; and I do hereby declare the following to be a full, clear, and exact description of the invention, such as will enable others skilled in the art to which it applies to make and use the same.

My invention relates to improvements in vises for work-benches; and it consists in means for securing cushions to the inner faces of the jaws of a vise, as will be hereinafter fully described and claimed.

In the accompanying drawings, Figure 1 is a perspective view of a work-bench, showing my improved vise. Fig. 2 is a detail perspective view of one of the jaws of the vise. Fig. 3 is a detail of the securing-rod.

The work-bench A and the vise B are of the usual or any preferred construction, the vise consisting of the parts or jaws C D, connected by a screw E, as shown. To the inner faces of the jaws C D, at the upper ends of the same, I secure the elastic cushions F and f, which are composed of rubber plates.

In practice the article being operated upon is placed in the vise in the usual manner and when the jaws are closed will be held between the cushions. The rubber will adhere closely to the article, thereby holding the same very firmly while it will be prevented from coming in contact with the hard jaws and the liability

to injury is consequently overcome. The 35 cushion f is secured to the face of the jaws C by nails or screws, while the cushion F is arranged to cover the face of jaw D and have its extended ends secured by passing under the rods H, as clearly shown. The rods H are 40 placed on either edge of the jaw B and securely held in position by passing through the eyes h, which are secured in said jaws and hold the rods slightly away from and parallel with the jaws. The rods H are preferably 45 made of copper or other yielding metal, so that the end G of the cushion can be entered between it and the jaw, when by tightening the nut I the rod H is straightened and brought to bear firmly against the end of the cushion, 50 thereby securing the same.

Having thus described my invention, what I claim, and desire to secure by Letters Patent, is—

The combination of the stationary vise-jaw 55 C, having the rubber cushion f secured to its face, the movable jaw D, having at its edges the upper and lower eyes h, the cushion F, having the extended ends, and the binding-rod H, having the threaded lower ends and 60 the nuts working on said ends, substantially as set forth.

In testimony whereof I affix my signature in presence of two witnesses.

ROBERT S. COOPER.
